(57) **CLAIM**

We claim the ornamental design for a saw blade, as shown and described.

DESCRIPTION

FIG. 1 is a perspective view of a first embodiment of a saw blade showing my new design.

FIG. 2 is a first side elevation view of FIG. 1.

FIG. 3 is a second side elevation view of FIG. 1.

FIG. 4 is a top plan view of FIG. 1.

FIG. 5 is a bottom plan view of FIG. 1.

FIG. 6 is a front elevation view of FIG. 1.

FIG. 7 is a rear elevation view of FIG. 1.

FIG. 8 is a perspective view of a second embodiment of the saw blade.

FIG. 9 is a first side elevation view of FIG. 8.

FIG. 10 is a second side elevation view of FIG. 8.

FIG. 11 is a top plan view of FIG. 8.

FIG. 12 is a bottom plan view of FIG. 8.

FIG. 13 is a front elevation view of FIG. 8.

FIG. 14 is a rear elevation view of FIG. 8.

FIG. 15 is a perspective view of a third embodiment of the saw blade.

FIG. 16 is a first side elevation view of FIG. 15.

FIG. 17 is a second side elevation view of FIG. 15.

FIG. 18 is a top plan view of FIG. 15.

FIG. 19 is a bottom plan view of FIG. 15.

FIG. 20 is a front elevation view of FIG. 15; and,

FIG. 21 is a rear elevation view of FIG. 15.
